UNITED STATES PATENT OFFICE.

ORLANDO P. SMITH, OF NEW YORK, N. Y.

PEN-RACK.

Specification forming part of Letters Patent No. **35,786**, dated July 1, 1862.

To all whom it may concern:

Be it known that I, ORLANDO P. SMITH, of the city, county, and State of New York, have invented a new and Improved Pen-Rack; and I do hereby declare that the following is a full and exact description thereof, reference being had to the accompanying drawings, and to the letters of reference marked thereon.

My invention consists in the application of a flange, or an entire wheel or disk made of india-rubber, gutta-percha, or other elastic material, to the usual metallic stands or bases, in the following manner: The india-rubber, gutta-percha, or other elastic flange or wheel, marked R, is firmly secured to the metallic stands, marked M, by such means and in such form as the style of rack desired may require.

That my invention may be the better understood I annex the following explanations:

To the base of Figure 1, marked M, I fasten an upright post, P, of any required height, near the top of which I make a shoulder. Upon this shoulder I place a wheel, marked R, Fig. 4, which may be all of india-rubber, or with a metallic center and an elastic or rubber flange upon the periphery, the india-rubber or elastic flange being notched, as seen by Fig. 4, sufficiently deep to receive and hold the pen, as represented in Fig. 1, the said wheel revolv-

ing upon the post P, so that any pen or pencil desired may be taken, the rubber grasping all other pens sufficiently tight as to prevent their being displaced until required for use.

Figs. 2 and 3 represent one style of the usual metallic rack, to which I attach the elastic flange R², which is also notched, to a grooved piece of metal, marked M², reaching from one to the other of the uprights, marked O, which are made fast to the base M. Near the base I place a rod, A, extending from one to the other of the uprights O, to shield the pen, which rests in a receding position from the base M. (See Fig. 3.)

What I claim as my invention, and desire to secure by Letters Patent, is—

The application of a notched flange or strip of india-rubber, gutta-percha, or other elastic material, as a pen-rack, in all and every form in which the same may be applied, the elasticity of the material firmly grasping the pen or pencil, so that when any one may be taken from the rack all others remain fast in their positions.

ORLANDO P. SMITH.
